UNITED STATES PATENT OFFICE.

WILLIAM ORTWIG, OF ST. JOSEPH, AND EARL C. BRYANT, OF SPRINGFIELD, MISSOURI.

FOLDING LADDER.

1,129,003.

Specification of Letters Patent. Patented Feb. 16, 1915.

Application filed April 16, 1914. Serial No. 832,238.

To all whom it may concern:

Be it known that we, WILLIAM ORTWIG, a citizen of the United States, residing at 220 Fleeman street, St. Joseph, in the county of Buchanan and State of Missouri, and EARL C. BRYANT, a citizen of the United States, residing at Springfield, in the county of Greene and State of Missouri, have invented certain new and useful Improvements in 5 Folding Ladders; and we do declare the following to be a full, clear, and exact description of the invention, such as will enable others skilled in the art to which it appertains to make and use the same.

10 This invention relates to new and useful improvements in step ladders and more particularly to a step bracing construction therefor, and the primary object of the invention is to provide an improved construction for bracing the steps of a ladder whereby to securely retain the same in position under all conditions.

15 A further object of the invention resides in providing a knee brace between the steps of a ladder and the side bars thereof.

20 A still further object resides in providing an improved means for securing the knee brace in position.

25 Still another object of the invention resides in providing a construction which is simple and inexpensive and one which will be extremely efficient in use.

30 With these and other objects in view, our invention consists in the novel features of 35 construction, combination and arrangement of parts as will be hereinafter referred to and more particularly pointed out in the specification and claims.

35 Figure 1 is a side elevation of a ladder 40 constructed in accordance with our invention; Fig. 2 is a front elevation thereof; Fig. 3 is a perspective view of a detail of the invention; Fig. 4 is a similar view of the knee brace; Fig. 5 is an inverted perspective 45 view of one of the plate-like arms; Fig. 6 is an enlarged fragmentary side elevation, partly in section, of the pivotal connection between the ladder and support therefor; Fig. 7 is a section as seen on line 7-7 of 50 Fig. 1; Fig. 8 is a plan view, partly in section, of the ball bearing pivot connection; and Fig. 9 is a section as seen on line 9-9 of Fig. 2.

55 In describing the invention, we shall refer to the drawings in which similar reference characters designate corresponding parts

throughout the several views and in which, 1 indicates a ladder comprising the side bars 2 which tend to converge upwardly and the steps 3 which are supported between said side bars. The manner of securing and supporting the steps in position between the side bars, forms the essential part of this invention which will be hereinafter more particularly set forth.

60 Pivotally secured to the outer face of the side bars 2 at the upper ends thereof through the medium of the ball bearing connections 4, are the additional side bars 5 of a support for the ladder. These side bars 5 are braced 65 in position by means of the upper and lower transverse bars 6 and the diagonal cross bars 7. This complete support is adapted to receive the ladder between the side bars thereof in folding the device, the bars 6 and 7 limiting the movement in one direction of 70 the support and ladder proper with respect to one another. In order to limit the swinging movement of the ladder and support 75 with respect to one another in opposite directions, slotted bars 8 are provided, the same being pivoted at their one ends as indicated at 9 to the inner faces of the side rails 5. Studs 10 are provided on the outer faces of the side rails 2 which are extended 80 through the slots of said bars and through this medium it is obvious that the outward 85 swinging movement of the ladder will be limited.

85 The usual transverse grooves or slots are 90 provided on the inner faces of the side rails 2 of the ladder which form seats for the ends 95 of the steps 3. We have also provided an additional and improved means for bracing and securing said steps in position and to 100 this end, substantially triangularly designed strips or plates 11 are applied to the outer faces of the side rails 2 contiguous with the horizontal planes of the steps 3. The one side edge of each strip is arranged flush with 105 the rear edge of the side rail and one adjacent side edge is substantially in the same horizontal plane with the plane of the under face of the adjacent step, as clearly shown in the drawings. Formed on the inner face 110 of each of the triangularly designed strips or plates 11 at the corners thereof, are the laterally extending projections 12 which are designed to be received snugly in sockets or 110 openings 13 in the side rails 2 and bores are provided in said projections which extend completely therethrough and through the

plate or strip 11. We prefer to so construct these plates or strips 11 as to position the outer faces of the projections 12 about midway of the faces of the side rails of the ladder, but the bores continue through said side rails of a diameter equal to bore of the projections. It will thus be seen that a pair of sockets are provided in a plane just below the under face of each step at each end of the ladder, while an additional socket is provided in a plane a short distance therebelow. The projections 12 within these sockets form bearings for purposes to be hereinafter described.

Secured to the upper face of each step at points adjacent the ends thereof, are the strips or elongated plates 14 which are counter-sunk in place and have the ends thereof bent downwardly to engage the front and rear edges of said step. These strips or plates may be secured in place by means of bolts or the like 15, the heads of the latter being preferably counter-sunk in the top faces of said plates, so as not to interfere with the smooth surface of said steps. Secured to the under faces of each step by means of the same bolts 15 which secure the plates 14 in place, are the laterally projecting plates or arms 16. These plate-like arms 16 may be additionally secured in position if desired, so as to be firmly supported in place and the outer ends thereof are provided with integral pins or studs 17 which are threaded for engagement with the threaded bores of the upper projections 12 on said plates or strips 11. These projections 12 form substantially bearings for the reception of the projections 17 of the plate-like arms 16 and it will be seen that when said arms 16 are properly positioned, the same will be secure in their fastenings and support the steps at both ends thereof.

In order to secure each plate 14 in position on the steps, a pair of bolts is provided and engaged with the lower end of the bolt adjacent the rear edge of the step is an angularly bent end of a knee-shaped brace or support 18. This knee or support is preferably bolt-like in formation and has the upper end which is engaged by one of the bolts 15 flattened as indicated at 19 to provide a bearing surface thereon. The lower angular end of the knee-shaped support 18 indicated as 20 is bent outwardly and threaded for engagement in the bearing or projection 12 at the lower portion of the adjacent strip or plate 11. Nuts are of course applied to the bolts 15 and when turned home will securely retain the parts engaged by the bolt in their respective positions. It will be seen that the nuts on the bolts 15 nearer the rear edge of each step retain the plates 14, 16 and the supports 18 in position on the step. The knee-shaped supports 18 when properly positioned as described, will securely brace

the steps in position in addition to the bracing means already described so that said steps are securely held in position between the side rails and adapted to bear all weights.

From the foregoing description of the construction of our improved step bracing mechanism for ladders, the manner of applying the same to use will be readily understood and it will be seen that we have provided a 75 bracing means which is simple and durable in construction, inexpensive to manufacture and one which will be very efficient in use.

While we have particularly described the elements best adapted to perform the functions set forth, it is obvious that various changes in form, proportion and the minor details of construction may be resorted to without departing from the spirit or sacrificing any of the principles of the invention. 85

Having thus described our invention, what we claim as new is:

1. In a ladder construction, the combination with a side rail and a step therefor; of a plate applied to the outer face of said side rail and having internally threaded projections thereon received in said side rail and forming bearings therein, plates secured to the under face of said step having projections formed thereon and engaged with certain of the aforesaid threaded bearings to brace the step in position and additional means in connection with the step and another of said threaded bearings to additionally brace said step with respect to the side 90 rail. 95

2. In a ladder construction, the combination with a side rail and step therefor; of a plate applied to the outer face of said side rail and having projections thereon received in said side rails, said projections being designed to form bearings therein, plates secured to the under face of said step having projections thereon received in certain of the aforesaid bearings to brace the step to the side rail, and a knee-shaped support also secured to the under face of said step and having one end thereof engaged with another of said bearings to additionally support said step in position with respect to the 110 side rail. 115

3. In a ladder construction, the combination with a side rail and step therefor; of a triangularly designed strip applied to the outer face of the side rail and having inwardly extending projections received through said side rail, said projections being designed to form bearings in said side rail and a pair of said bearings being arranged in substantially the same horizontal 125 plane, a pair of plates applied to the under face of the step and having projections on the outer ends thereof received in the last mentioned pair of bearings to brace the step, and a knee-shaped supporting arm also se- 130

cured at its one end to said step and having its other end received in the other of said bearings whereby to brace the step and side rail with respect to one another.

5 4. In a step construction for ladders, the combination with a side rail and step therefor, of a triangularly designed strip applied to the outer face of the rail having projections at the corners thereof received 10 through said rail, said projections being designed to form bearings and a pair of said bearings being arranged substantially in the same horizontal plane, a pair of plates secured to the under face of said step and having projecting studs formed on the outer ends thereof received in the last mentioned pair of bearings to brace said step, and a knee-shaped support secured at its one end to the under face of said step by the same 15 means securing one of said plates thereto, the opposite end of said knee-shaped support being extended outwardly and received in the other of the aforesaid bearings.

5. In a step bracing construction for ladders, the combination with a side rail and step therefor, of a triangularly designed strip applied to the outer face of said rail having projections at the corners thereof received through said rail, said projections 25 being designed to form bearings and a pair of said bearings being arranged in substan-

tially the same horizontal plane, a plate extending transversely of the upper face of the said step adjacent the side rail, the ends of said plate being depended and engaged 35 with the front and rear edges of the step, a pair of plate-like arms applied to the under face of said step and having projections at the outer ends thereof received in the last mentioned pair of bearings, means extending 40 through said step for simultaneously securing the plate and arms thereto, and a knee-shaped support having one end thereof engaged with a portion of the last mentioned means to secure the same to the 45 under face of said step, the opposite end of said knee-shaped support extending outwardly and engaged with the other of the aforesaid bearings, whereby to securely brace said step with respect to the side rail. 50

In testimony whereof we have hereunto set our hands in presence of two subscribing witnesses.
